ABSTRACT OF THE DISCLOSURE

An impervious corrosion-resistant perforated tubular holder for supporting therearound a package of yarn to be dyed. The holder consists of a tubular core shielded by an electrically conductive surface to which at least one electrolessly plated metallic coating is bonded. The core may be composed of thermoplastic acrylonitrile butadiene styrene, phenol, polyacetyl or polystyrene, and the metallic coating of copper, nickel or chromium.

This invention relates to yarn holders and more especially to perforated textile dye tubes around which yarn is wound to form a package through which dye, bleach and other solutions may be circulated.

In operation, the tube and yarn wound thereon is placed in a chamber containing a hot aqueous chemical solution which is circulated and recirculated through the tube perforations and the surrounding yarn. The chemical composition of many of these solutions, especially when heated, are highly corrosive thereby requiring great care in the selection of materials from which the tubes are made.

Heretofore, dye tubes have been made from plastic materials (see Patent No. 2,746,280) as well as from corrosive-resistant metals (see Patent No. 1,719,703), but such prior art tubes are objectionable under modern conditions both as to performance and cost. Conventional tubes made entirely of corrosion-resistant metal can be produced only at an excessive cost which is normally passed on to the consumer or purchaser. Where the tubes are made entirely of plastics or resins, there is usually an excessive bulk, a critical deficiency in rigidity and surface hardness, and an objectionable high moisture absorption characteristic.

It is an object of this invention to provide a plastic dye tube core or substrate which is coated or plated with a metal so as to overcome the aforementioned difficulties experienced in this art.

It is another object of this invention to provide a dye tube composed of a relatively thin inner plastic core which is entirely encased within and reinforced by a hard corrosion-resistant metallic shell whereby the bulk and weight of the tube will fall within permissible limits, the surface properties greatly improved, and the manufacturing cost substantially decreased.

Some of the objects of this invention having been stated, other objects will appear as the description proceeds when taken in connection with the accompanying drawings, in which:

FIGURE 1 is an elevation of my improved dye tube;
FIGURE 2 is an end view of FIGURE 1;

FIGURE 3 is an enlarged sectional view through a portion of the dye tube wall and taken along line 3—3 in FIGURE 1, and

FIGURE 4 is a diagram schematically illustrating one of the processes employed in making the dye tube.

Referring more specifically to the drawings, the numeral 10 designates broadly my improved dye tube which is composed of a plastic or resin core or substrate 11, a copper plating or coating 12 secured to or adhered to the

2

outer surfaces of the core, a nickel plating 13 on the outer surfaces of the copper coating, and a chromium plating 14 on the outer surfaces of the nickel plating. In one form of the invention, the plating 12 consists of 5 electroless copper and the platings 13 and 14 of bright electrolytic nickel and chromium respectively. Although a plurality of metallic coatings or platings are shown and described, the invention contemplates one or more metallic coatings or platings which encase or adhere to the outer surfaces of a molded plastic or resinous dye tube core 10 whereby the outer metallic tube surfaces will be resistant to chemical corrosion and seal the inner plastic core from moisture and from such corrosion.

The finished tube 10 has a plurality of perforations 15 therein through which yarn treating solutions are adapted to flow and through the yarn (not shown) which may be wound around the tube.

The dye tube according to the invention is made by subjecting certain types of plastics or resins to an injection 20 molding process to thereby form the core or substrate 11 (FIGURE 3) into a shape similar to the conventional dye tube, then preparing or conditioning the exterior surfaces of the molded core for the reception of a metallic plating, and finally depositing one or more metallic platings 25 onto the prepared surfaces.

Numerous plastic compositions or resins are suitable for forming the core 11 prior to the deposition of the platings or coatings thereon. Specific examples of suitable compositions include: polyacetals such as commercially available Delrin; phenolic plastics; polycarbonates; polystyrene; and thermoplastic acrylonitrile butadiene styrene commercially designated as Cycolac EP-3510. Of the above-named compositions, Cycolac EP-3510 has been found especially suitable since it possesses a good balance 35 of properties such as rigidity, toughness, heat resistance and low moisture absorption.

Several known processes may be employed to condition or prepare the outer surface of the dye tube core 11 for the reception of a plated or coated metallic outer surface. Such processes develop adhesion of metal deposits to the plastic core surfaces and include (1) the dispersal 40 of a metallic powder in the plastic prior to molding to render it electrically conductive, (2) the deposition of a conductive metal film on the core by chemical reduction, (3) encapsulation or a heavy electrodeposit surrounding the entire outer surface of the core, (4) treating the core or substrate with a colloidal metal solution of a metal catalytic as disclosed in Patent No. 3,011,920, (5) treatment of the molded core according to the process as reported in the April 1964 issue of Products Finishing, and 50 similar to the first six steps illustrated in FIGURE 4 of the drawings.

Conditioning process 5, when employed upon a dye tube molded from Cycolac EP-3510, has been found to produce optimum results and will be described in detail as representative. It is to be understood, however, that the invention resides in the dye tube construction and composition and therefore is not limited to the manner or process by which it is produced, but instead, includes various combinations of the above-mentioned core compositions and of the plating or coating materials therefor.

One typical process of plating a dye tube core 11 made of Cycolac EP-3510 is diagrammatically illustrated in FIGURE 4 and outlined below. This process is described in greater detail in an article entitled "Electroplating on Plastics" published in the April 1964 issue of Products Finishing. The steps in the process are substantially as follows:

- (1) Alkali cleansing with a detergent or similar base;
- (2) Acid neutralizing with acetic or hydrochloric acid to prevent subsequent acid solutions from being neutralized;

- (3) Surface conditioning (Enplate Conditioner 470, April 1964 issue, Products Finishing);
 (4) Sensitize;
 (5) Activate;
 (6) Electroless copper plate;
 (7) Bright nickel plate;
 (8) Hard chromium plate.

The above process will produce a hard, wear and corrosion resistant surface on the plastic core 11 capable of withstanding the operating temperatures and acidic dye and other treating solutions encountered in yarn treating operations.

In the drawings and specification there have been set forth preferred embodiments of the invention, and although specific terms are employed they are used in a generic sense and not for the purpose of limitation, the scope of the invention being defined in the following claims:

I claim:

1. An impervious corrosion-resistant holder for supporting therearound a package of yarn to be dyed comprising a tubular plastic core having spaced perforations extending through the wall thereof, the surfaces of said wall and perforations being electrically conductive, and at least one electrolessly plated metallic coating bonded to said surfaces to thereby shield said core while permitting dye solutions to flow through the package and perforations to and from the interior of the holder.

2. A dye tube as defined in claim 1 wherein said core comprises thermoplastic acrylonitrile butadiene styrene.

3. A dye tube as defined in claim 2 wherein said plating comprises successive layers of copper, nickel and chromium.

4. A dye tube as defined in claim 1 wherein said core comprises thermoplastic phenol plastics.

5. A dye tube as defined in claim 1 wherein said core comprises thermoplastic polyacetal compositions.

6. A dye tube as defined in claim 1 wherein said core comprises polycarbonate compositions.

7. A dye tube as defined in claim 1 wherein said core comprises polystyrene.

8. A dye tube as defined in claim 3 wherein said successive layers are electroless copper, electrolytic bright nickel and electrolytic hard chromium.
